CYMBAL DRUMSTICK

Raymond D. Barker, 7744 Satsuma Ave.,
Sun Valley, Calif. 91352

Filed Feb. 12, 1970, Ser. No. 21,408

Term of patent 14 years

Int. Cl. D17—04

U.S. Cl. D56—1

FIG. 2.

FIG. 3.

FIG. 4.

FIG. 5.

FIG. 1 is a perspective view of a cymbal drumstick, showing my new design;

FIG. 2 is a side elevational view to an enlarged scale, the opposite side being substantially a mirror image thereof;

FIG. 3 is a top plan view, to an enlarged scale, the bottom being substantially a mirror image thereof;

FIG. 4 is an end elevational view, looking at the right end in FIG. 2; and

FIG. 5 is an end elevational view thereof looking at the left end in FIG. 2.

I claim:

The ornamental design for a cymbal drumstick, substantially as shown and described.
